US00D687031S

(12) **United States Design Patent**
Chen et al.

(10) **Patent No.:** US D687,031 S
(45) **Date of Patent:** ** Jul. 30, 2013

(54) **PORTABLE ELECTRONIC DEVICE**

(75) Inventors: **Yi-Chia Chen**, Taipei (TW); **Chang-Yi Tseng**, Taipei (TW); **Liang-Jen Lin**, Taipei (TW); **Yi-Chang Chen**, Taipei (TW); **Ke-Ming Chen**, Taipei (TW); **Hsien-Kuang Chiu**, Taipei (TW); **Cheng-Yao Huang**, Taipei (TW)

(73) Assignee: **ASUSTeK Computer Inc.**, Taipei (TW)

(**) Term: **14 Years**

(21) Appl. No.: **29/423,304**

(22) Filed: **May 30, 2012**

(51) **LOC (9) Cl.** 14-02

(52) **U.S. Cl.**

USPC **D14/327**; D14/315

(58) **Field of Classification Search**

USPC ..... D14/315-327, 341, 371; D18/1, D18/2, 7, 11; 235/145 A, 145 R; 341/22, 341/23; 345/104, 156, 168, 169, 173; 361/679.08, 679.09, 679.11, 679.26, 679.27

(57) **CLAIM**

The ornamental design for a portable electronic device, as shown and described.

DESCRIPTION

FIG. 1 is a perspective view according to our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is another perspective view according to our new design;

FIG. 9 is a front elevational view according to our new design in a closed position;

FIG. 10 is a rear elevational view thereof;

FIG. 11 is a left-side elevational view thereof;

FIG. 12 is a right-side elevational view thereof;

FIG. 13 is a top plan view thereof; and,

FIG. 14 is a bottom plan view thereof.

The broken lines shown in figures illustrate environmental structures and form no part of the claimed design.
